UNITED STATES PATENT OFFICE.

MYRA JULIET TAYLOR, OF SYDNEY, NEW SOUTH WALES, AUSTRALIA.

WAIST.

1,224,100.

Specification of Letters Patent. Patented Apr. 24, 1917.

Application filed May 7, 1915. Serial No. 26,578.

To all whom it may concern:

Be it known that I, MYRA JULIET TAYLOR, a citizen of the Commonwealth of Australia, residing at Sydney, New South Wales, Australia, have invented a new and useful 5 Waist, of which the following is a specification.

This invention relates to a flexible waist, having its respective parts so constructed 10 and arranged as to provide for the free and unrestricted movement of the wearer, by adapting itself to the movement of the body in any direction, at the same time causing a conscious feeling of support to those parts 15 of the body which it has hitherto been considered necessary should be supported by stays or corsets composed partly of metal and bone reinforcing materials, such being considered indispensable in order to preserve 20 the true shape and contour of the wearer's body.

It is known that wearing such corsets occasions much discomfort on account of their non-elasticity.

25 The present invention is intended to eliminate the use of such stiffening materials in the formation of a flexible camisole, but at the same time provide for the use of supporting devices by peculiarly shaping and treating 30 the materials of which it is composed, and then in the method of drawing the fitting parts into close contact with those portions of the body where it is desired there should be created the feeling of added support.

35 Further desired objects to be attained in this form of camisole stayette, is its cheapness, and that it is washable and capable of prolonged wear.

40 Referring to the accompanying drawings, which form part of this specification:

Figure 1 is a back elevation of a complete camisole stayette (as designed by the inventor for a full bodied person) showing its appearance when the bodice is spread out flat with the back part overlying the front part, exposing to view the shoulder loops, the under-arm and other seams, with darts and V elastic parts which are essential to obtain 45 true form and accurate fitting, also suspenders on either side of the elastic parts. The position of the crossed bands is indicated by 50 dotted lines only.

Fig. 2 is a similar elevation of Fig. 1, 55 but with the crossed bands and their guide

loops shown in position, and partially covering portions of the seams and stiffened parts.

Fig. 3 is a front elevation of the spread out garment with the bodice parts overlaid as in Fig. 1, showing the general arrangement of the seams, darts, breast hollows, and V elastic parts, the position of the crossed bands being indicated by dotted lines only. 60

Fig. 4 is a similar elevation to Fig. 3, but with the crossed bands shown in their fastening position, with the loops also in place. 65

Fig. 5 is a right hand side elevation, showing the bust fitted shape of the garment, with its various parts disposed in their relative positions to obtain the desired rigidity 70 and elasticity.

In the figures the bodice is shown—cut to the required shape—composed of a number of parts, the back being formed with the parts A and A¹, connected together by the 75 back stiffening seam B, positioned so as to overlie the spinal column of the wearer. Each half is cut away to form a center V in which elastic webbing C is inserted and stitched in position to the edge seams C¹ 80 which are continued around the bottom part of the garment. The front parts A² and A³ are united to back pieces A¹ and A by the stitched under-arm stiffening seams B¹ and B² respectively. 85

Each front piece has its V shaped cut with the elastic webbing D and D¹ inserted therein and secured by the stitched seams D² and D³, which are further continued to the overlapping front edges, continuing then upward to the top, the one side being pierced with holes to receive the buttons E by which the garment is fastened. Both of these upward overlapping seams are provided with 90

V-shaped incisions in which the elastic webbing E¹ and E² are stitched. This webbing provides relief from the drag of the front suspenders F, while the back suspenders G are relieved of their drag by the elastic webbing C, D, and D¹, which are also serviceable 100 in the expansive body movement occasioned by freedom of action in the lower limbs from the hips downward. The curved fitting waist shape is obtained by the use of the upwardly directing darts D⁴ and D⁵ shown extending above from the webbing D and D¹ 105 and also by the curved seams B¹ and B² which are likewise used for uniting the back and front parts.

Seam B¹ and dart D⁴ are united by the 110

spiral strengthening seam B^3 and the seam B^2 and dart D^5 and similarly united by the spiral seam B^4 . The object of the spiral seams is to insure the accurate fitting of the 5 parts and likewise to insure in the mind of the wearer a consciousness of support to the body which is further enhanced by the adjustment of the straps hereinafter referred to. The overlapping V's E^1 and E^2 have 10 associated with them the curved double pointed stitched darts H and H^1 which besides giving added strength to the webbed parts are also serviceable in obtaining the requisite fitting shape of the article. To insure 15 equal movement upwardly and downwardly of the V parts E^1 and E^2 , a securing button E would be located in the center of the overlapping part. Other curved darts I and I^1 shown on Fig. 3 extending 20 downwardly upon the shoulder straps J and J^1 close to the breast hollows K and K^1 , further assist in shaping the article at that part to obtain a rounded formation and also take up the strain incidental to the use of 25 cross over straps hereinafter referred to. The breast hollows K and K^1 , are margined with stitched bands K^2 and K^3 . Similarly the external edges of the arm holes L and L^1 , and the front and back neck formations 30 M and M^1 , are likewise stitch banded, to preserve the general contour of the garment. Cross straps N and N^1 are secured to the back of the garment through the medium of shoulder straps J and J^1 and extend partially 35 around the armhole to the under arm stiffening and joining seams B^1 and B^2 . The said straps N and N^1 are thence partly extended around the waist and across the front of the garment terminating in the form of 40 a belt which may be united by a fastener in the form of a buckle and the like. For the guidance of the cross over bands in the desired direction loops O and O^1 are provided partially covering the underarm seams B^1 and B^2 45 and other guiding loops P and P^1 secured on the front of the garment serve to keep the strap ends in their proper position at the front. It is to be understood that these cross bands are only united to the garment at the parts indicated so as to obtain the requisite straining effect and further the necessary freedom for adjusting other parts to the body in their rightful positions. Such rightful positions being in the diagonal direction indicated 50 in the back view Fig. 2 and in the horizontal position of the united ends in Fig. 4.

It is essential that these cross bands shall be stiffened by stitching the fabric at suitable intervals in the length of the material to prevent creasing and moreover that when 60 in position a certain amount of exactitude shall be observed in their disposition and arrangement to insure their meeting over the spinal column seam B .

Having now described my invention, what 65 I claim as new and desire to secure by Letters Patent is:—

1. In an improved stayette for body wear, a body part consisting of a back part formed of two pieces of fabric united in the center 70 with a stiffening seam adapted to overlie the spinal column, a V shaped cut out marginal seamed opening extending downwardly and outwardly from said stiffening seam; elastic in the said opening, united to 75 the margins thereof, two front parts of the said garment each united to one half of the said back portions by an under arm seam extending from the arm hole downwardly to the bottom edge of the garment, a marginal 80 seamed V shaped opening formed in the bottom part of each of the said front parts, elastic in each of the said V shaped parts, darts extending upwardly from each of the said V parts, a spiral seam arranged to 85 unite the said darts with the said underarm seams, as described and shown and for the purposes set forth.

2. In an improved stayette for body wear comprising a two-part back united together 90 by a centrally stiffened seam terminating short of the lower ends of the parts, an elastic gusset connecting the lower ends of said parts, a two-part front each provided with a dart and having overlapping front 95 edges, said two-part front being connected with the two-part back by under arm seams, an elastic gusset secured in the overlapping edges of the front part, a pair of cross bands connected to one end of the two-part 100 back and adapted to extend through loops disposed on the sides and front portions of the stayette and means for uniting the free ends of the cross bands together.

In testimony whereof I have hereunto subscribed my name in presence of two witnesses.

MYRA JULIET TAYLOR.
